Des. 209,966
Patented Jan. 23, 1968

209,966

INSULATING COVER FOR ELECTRICAL CONNECTORS OR THE LIKE

Suel Grant Shannon, Harrisburg, and William David Neville, Camp Hill, Pa., assignors to AMP Incorporated, Harrisburg, Pa.

Filed Sept. 30, 1966, Ser. No. 4,114

Term of patent 14 years

(Cl. D26—10)

FIGURE 1 is a perspective view of an insulating cover for electrical connectors or the like showing our new and ornamental design;

FIGURE 2 is a top plan view of the insulating cover shown in FIGURE 1;

FIGURES 3 and 4 are end elevational views of the cover shown in FIGURE 2;

FIGURE 5 is a left side view of the insulating cover;

FIGURE 6 is a bottom plan view of the insulating cover; and

FIGURE 7 is a right side view of the cover.

We claim:

The ornamental design for an insulating cover for electrical connectors or the like, substantially as shown.
